UNITED STATES PATENT OFFICE.

JOSEPH F. REIRDON, OF KINGSTON, PENNSYLVANIA, ASSIGNOR TO THE ADDER MACHINE COMPANY, OF WILKES-BARRE, PENNSYLVANIA, A CORPORATION OF PENNSYLVANIA.

ELIMINATION AND SPECIAL-SIGNAL MECHANISM.

1,294,704.

Specification of Letters Patent.

Patented Feb. 18, 1919.

Application filed May 24, 1912. Serial No. 699,576.

To all whom it may concern:

Be it known that I, JOSEPH F. REIRDON, a citizen of the United States, residing at Kingston, Luzerne county, Pennsylvania, have invented new and useful Improvements in Elimination and Special-Signal Mechanisms, of which the following is a specification.

This invention relates to calculating machines, and more particularly to elimination devices and special signal mechanisms therefor, whereby the operation of a manually-controlled member, as a key, sets mechanism to disable a part of the machine, and to effect the imprint of a distinguishing character to indicate that such part was disabled, at that particular operation of the machine.

Furthermore, the invention is directed to a special sign printing mechanism to distinguish selected printed items from others in the list.

Commonly, calculating machines of the Wales type, have been equipped with eliminating mechanisms directly operated by depression of a key to disable a part of the machine, as the registering or printing mechanisms, prior to the operation of the main drive shaft.

The printing of a character coincidently with the operation of the usual printing mechanism to indicate that the registering mechanism was disabled during such operation is not new in this invention.

So far as I am aware, however, no means has ever been provided to print a character to indicate that the printing mechanism was disabled during an effective operation of the registering mechanism. The non-print mechanism, as usually operated, prevents the functioning of the regular printing mechanism, without affecting the registering mechanism or the paper feeding mechanism. Hence, the item set up on the keyboard is registered and the paper is fed to leave a blank space or spaces between the printed items. It follows in adding a column of items, one or more of which have been registered but not printed, that the total, when printed, will be a total of the amounts registered, and will not accord with the sum of the items printed. This is confusing, and permits the ready falsification of records, as by feeding the paper backwardly, after an operation of the machine

with the non-print key depressed, and printing an item in the space left blank by the former non-printing operation. 55

One object of this invention is to print a signal each time the regular printing mechanism is disabled by operation of the non-print key, to indicate on the paper, such condition of the printing mechanism, and to prevent manipulation of the record. 60

Furthermore, machines of the well-known Wales type have a clear signal mechanism set in the operation of taking a total and clearing the machine, to automatically print a signal adjacent the first item printed after such totaling and clearing operation, to indicate that the machine was clear when the first item was printed. The absence of such printed signal adjacent the item at the head of the list indicates that the counters had registered some amount, prior to the registration of said first item, and consequently the operator is placed upon his guard, as the footing or total registered and printed may not be the correct total of the items printed in that column. 70 75

Another object of this invention is to effect the imprint of said clear signal associated with the imprint of the non-print signal, when said non-print key is operated to prevent the printing of the first item set up after a totaling and clearing operation. 80 85 This arrangement will determine for the operator whether the machine was clear when the first item of a list was introduced into the machine, even though said item was not printed, thereby relieving the operator of anxiety or indecision on this point, and also preventing manipulation of the record. 90

In lists wherein the first item or items are registered only, and not printed, if the operation of the clear signal mechanism is suspended until the recording of the first printed item, it would tend to confuse the operator, and would, in fact, cease to be a clear sign, under these circumstances, because by the registration of the first item or items without printing, the register would contain one or more items prior to the imprint of such clear signal. 95 100

A further object is the provision of a novel clear signal mechanism which is adapted to print independently of the regular item printing mechanism. 105

Another object is to improve the means

whereby the regular printing mechanism is disabled, the effectiveness of the non-printing mechanism being controlled by the operation of the main drive shaft itself, and is 5 in no way dependent for operation on the printing mechanism.

It is frequently desirable in listing a series of items, to designate particular or recurring items in the list, such as those relating to a 10

certain customer's account, for instance, so they may be readily distinguished from the mass of other items, and another object of this invention is to improve and simplify means for attaining this result.

15 In so doing, I have contrived a mechanism which can be used for the purpose of positioning other than signal types, relatively to the printing line.

A still further object of this invention 20 is to improve the non-add mechanism, whereby the registering mechanism is disabled, the non-add mechanism being set by a manually-operable member, as a key, and subsequently shifting to effective position by the

25 operation of the main drive shaft, thereby making the key touch easier and relieving the operator of the necessity for manually shifting the non-add mechanism to effective position. This object is also attained in the

30 non-print and special signal mechanisms.

In order to designate such non-added or unaccumulated items on the printed list, it is customary to provide means whereby a signal is printed adjacent said items, and 35 another object of this invention is to improve the mechanism by which this result is accomplished.

Heretofore, it has been customary to so arrange the non-add mechanism, that the 40 total and clearing mechanism could not be operated if the non-add key was depressed, and vice versa.

A further object of this invention is to 45 improve and simplify the means whereby the non-add mechanism is locked out of operation when the total and clearing mechanism is set, the non-add mechanism being arranged to be released from set position by the depression of the usual total key, thereby 50 preventing any interference with the operation of the registering mechanism in the usual operation of taking a sub-total, or of taking a total and clearing the machine.

Still another object of this invention is to 55 arrange the several special manually-operable members, or keys, on the keyboard subject to the control of the usual key-controlling devices, and to place a type carrier common to all, and having the several type 60 characters mounted therein, under the control of any of said keys.

It is customary in some calculating machines to provide mechanism to lock the depressed keys in actuated position and the 65 remaining keys against actuation, to prevent

the depression of more than one key in any one bank or row, other means being provided, if desired to prevent the depression of any keys after the machine has been started on an operation.

Another object of this invention is to provide improved and simplified means of this nature to coöperate with the special manually-operable members.

Other objects and advantages will be set 71 forth hereinafter, and particularly pointed out in the claims.

In the accompanying drawings, Figure 1 is a side view, showing one embodiment of my invention applied to the well-known 81 Wales adding and listing machine.

Fig. 2 is a plan view.

Fig. 3 is a side view, illustrating one form of mechanism to prevent the imprint of an item, and known as the non-print mechanism. This view also shows a means whereby a signal is set to print during the operation of the registering mechanism, said signal mechanism being in idle position, parts being broken away, and omitted.

Fig. 4 is a similar view, illustrating the position of the mechanism when the non-print key is depressed, the main drive shaft having started on its forward stroke.

Fig. 5 shows the means for setting the 95 member which disables the printing mechanism.

Fig. 6 is a detail perspective of the disabling member for the regular printing mechanism, and its shifter.

Fig. 7 is a view of the left-hand side of the well-known Wales adding and listing machine, showing the totaling and clearing mechanism which controls the setting of the clear signal mechanism. The totaling and clearing mechanism is shown in the act of setting the clear signal mechanism, the drive shaft being on its return stroke.

Fig. 8 is a similar view, showing the positions of the parts, when the clear signal is 111 set, the drive shaft having returned to initial position.

Fig. 9 is a detail perspective of the connection between the totaling and clearing mechanism, and the clear signal mechanism.

Fig. 10 is an enlarged detail view, showing a means to effect the imprint of the clear sign adjacent the imprint of the non-print sign, the mechanism being shown in idle position.

Fig. 11 is a similar view, showing the clear signal mechanism set for operation, as in Fig. 8.

Fig. 12 is a similar view, showing the means which disables the regular printing 121 mechanism, in effective position, with the clear signal about to be printed, parts being omitted.

Fig. 13 is a detail perspective of a switch controlled by the non-print mechanism to 130

effect the tripping of the clear signal mechanism.

Fig. 14 is a perspective of a stop to prevent depression of the non-print and other 5 keys, in the same bank during the operation of the drive shaft.

Fig. 15 is an enlarged detail side view, showing a key-locking and signal-positioning mechanism controlled by the special signal 10 keys, the mechanism being at rest.

Fig. 16 is a detail, illustrating the manner of tripping the key-lock, and also of operating the connection between the non-print or elimination key and the detent which normally 15 holds the disabling member for the printing mechanism idle.

Fig. 17 is a view similar to Fig. 15, showing the key-locking and signal positioning mechanism tripped.

Fig. 18 is a perspective of a means to restore the key locking mechanism to idle position.

Fig. 19 is a side view, showing a key-controlled mechanism to print a special signal 25 adjacent any desired item.

Fig. 20 is an enlarged detail side view of another elimination key to control the registration of items, and known as the non-add key, the key being shown depressed to adjust the mechanism to set position, parts being omitted.

Fig. 21 is a somewhat similar view, showing the non-add mechanism locked in operative position and about to be tripped to permit it to return to idle position.

Fig. 22 is an enlarged detail of a part of the non-add mechanism, shown just as it is about to return to idle position.

This invention in so far as it relates to 40 non-printing mechanisms constitutes an improvement upon the patents to Wales, 902,125, issued October 27, 1908, and to McFarland, 924,264, issued June 8, 1909.

In so far as the invention relates to non-add mechanisms, it is an improvement on the patent to McFarland, 880,159, issued February 25, 1908.

In so far as the invention relates to clear signal mechanisms, it constitutes an improvement on patent to Wales, 940,758, November 23, 1909.

Reference is also made to patent to McFarland, 842,232, January 29, 1907, illustrating a totaling and clearing mechanism; 55 McFarland, 874,107, December 17, 1907, illustrating a repeat key mechanism; McFarland, 940,708, November 23, 1909, showing a locking keyboard, and to Wales, 794,205, July 11, 1905, and 797,032, August 15, 1905. Features briefly referred to hereinafter are more fully disclosed in the above-named patents.

The invention is illustrated as applied to the well-known Wales type of calculator, in 65 which 1, (Figs. 1 and 2) indicates the side

frames between which are supported the keyboard mechanism, the registering or accumulating mechanism and the recording or printing mechanism.

The keyboard mechanism includes keys 2 arranged in rows from 1 to 9, if the decimal system is used, (Fig. 2), with their stems projecting through a key-plate 3 (Figs. 1 and 15), and connected each to one end of their respective levers 4, the opposite ends of which levers carry stops 5, arranged in rows corresponding to the rows of keys and project through a housing 6.

The registering or accumulating mechanism includes a series of drive members or 80 racks 7, arranged in line with the rows of stops 5 and supported on front and rear arms 8 and 9, swinging on cross shaft 10 and cross rod 11, respectively, mounted in the side frames 1. Springs 12 (Fig. 5) tend to 85 propel said drive members toward the stops 5, but are normally prevented from so doing by a restraining and restoring bail 13, held in arms 14 carried on a rock shaft 15, to contact the forward arms 8 and hold the drive 90 members retracted. A crank 16 having a cam slot 17 connects the rock shaft with an arm 18 fast on the main drive shaft 19. The free end of said arm 18 traverses the cam slot to rock the bail 13 relatively to the 95 drive members, and normally holds the bail in effective position against the supporting arms 8. Counters 20 are individually rotatable on an axle 21 mounted in arms 22 pivoted at 23 to the side frames 1 and supported out of engagement with the drive members by props 24 connected to the arms at 25. The lower ends of said props are slotted and rest upon a trip rod 26 carried by arms 27 loosely mounted on shaft 10. 105 Links 29 connect the trip rod 26 with the main drive shaft 19. A pinion 30 is fast with each counter to turn the same.

In an adding operation, depression of the desired keys 2, projects stops 5 into the paths of their coacting racks 7, the stops being held in effective position by well-known means, not shown.

The drive shaft 19 is then turned forwardly by a handle 32, for instance, to cause 110 the arm 18 to traverse cam slot 17 and swing the crank 16 to withdraw the restraining and restoring bail 13 and permit the springs 12 to advance the drive members or racks 7 forwardly until arrested by the stops 5, or 115 by the usual detents 31 which overlie the several series of stops, and arrest the drive members to prevent a registering operation thereof when not displaced by the projection of a stop in that series. The main shaft 120 19 on its forward stroke also swings the trip rod 26 forwardly, through links 29 to withdraw the props 24. Supports or legs 33 connected to the axle 21 contact rests 34 on the side frames as the props are withdrawn, 125 130

- to hold the counters idle while the racks are being advanced, said supports having slotted links 35 connected thereto. The ends of the trip rod 26 travel in the slots until after 5 the racks have been arrested, whereupon the rod strikes the outer ends of said slots to trip the supports 33 off the rests 34 and allow the counters to descend to mesh the pinions 30 with their respective racks 7 as the main 10 drive shaft approaches the end of its forward stroke. Springs 28 connected to the props 24 are tensioned by the outward or forward travel of the trip rod 26, to insure an immediate engagement of the pinions 30 and 15 drive racks 7 when the supports 33 are tripped.

Releasing the handle 32, when the drive shaft 19 reaches the end of its forward stroke, enables the usual restoring springs 20 (not shown), to return the shaft and its connected parts to normal position. The arm 18, during such return, rocks the crank 16 and its rock shaft 15 to press the restoring bail 13 against the forward arms 8 of 25 such racks as have advanced until arrested by the stops 5, to return them to normal retracted position. The racks, as they return, rotate the counters to register thereon the amount set up on the keyboard. The trip 30 rod 26 also swings the props 24 toward initial position, and after the racks have been restored, said props are raised by the trip rod to effect the disengagement of the counters from the racks and lift the supports 33 35 into line with their rests 34, so that the machine is ready for another operation.

The regular printing mechanism includes arms 36 (Figs. 5 and 7) fast with the rear supports 9 of the drive members, (Fig. 2), 40 and links 36^x connect arms 36 with type carriers 37, having types 38, so that the advance of the drive members 7 positions the types 38 relatively to the printing line on a platen 39. Devices to impress said types 45 on the paper include spring-driven hammers 41 (Figs. 5 and 7) journaled on a rod 73 and normally held retracted by individual latches 180 and by a catch 40 common to all the hammers. Spring-pressed 50 trip bars 181 tend to displace the individual latches, but are normally held idle by lugs 182 thereon which contact the lever arms 36. If a detent 31 lies in the path of a drive member, the lever 36 is not raised sufficiently 55 to enable the trip bar to become effective, and the individual latch holds its hammer against operation, when the catch 40 is withdrawn in the operation of the machine.

The positioning of the types 38 relatively 60 to the printing line by the levers 36, effects the release of the individual latches by freeing the corresponding trip bars to the action of their springs 183 and as the main drive shaft 19 approaches the end of its forward 65 stroke, the catch 40 connected therewith by

a linkage, not shown, is lifted to release the hammers which strike a series of plungers or firing pins 42 to drive them against the rear ends of the types 38 lying opposite the printing line, and effect the impression of 70 the types against the paper. A bail 43 (Figs. 10, 11 and 12) restores the hammers to cocked position, on the return stroke of the main drive shaft, where they are held by the catch 40 and latches 180, the trip bars 75 181 having previously been retracted by the retirement of the racks or drive members 7.

The foregoing mechanism is the well-known Wales printing means which is more fully shown and described in the patents 80 above referred to and particularly in Patents Nos. 794,205; 902,125 and 924,264. Furthermore, said mechanism is similar to that to be hereinafter disclosed in referring to the signal printing mechanism. 85

To take a total and clear the machine, a total key 44 (Figs. 7 and 8) is depressed. This key rocks a set lever 45, 45^a fast on shaft 10, the opposite end of which shaft carries similar set lever having an arm 46 90 (Fig. 1) corresponding to arm 45^a. Slotted links 47 connect arms 45^a and 46 with the legs or supports 33 and when said arms 45^a, 46 rock forwardly, said links swing the legs or supports out of line with their rests 34. 95 The main shaft, on its forward stroke, swings the trip rod 26 which travels in a descending arc, thereby lowering the props 24 and (the legs being disabled), the counters are engaged with the racks at the outset 100 of the forward stroke and prior to the release of the racks. A connecting bar 48 (Fig. 8) joined to arm 45^a, by a pin and slot connection 48^a, is shifted as the arm is rocked by the depression of its key, to bring 105 a cam edge 49 on said connecting bar against a crank 50 on a shaft 51 to rock said shaft and displace said detents 31 in the well-known manner.

The rack members 7 when released are 110 thus free to advance until arrested by the zero-resetting devices in a manner set forth, for instance, in Patent 842,232 above referred to, and not herein shown. This operation not only returns the counters to zero, 115 but positions types 38, corresponding to the total displayed by the counters just prior to the totaling and clearing operation, which total is printed in the usual manner as the main drive shaft approaches the end of its forward stroke. A locking means 52, on the drive shaft 19, indicated in Figs. 7 and 8, holds the total key depressed during the forward stroke, at the end of which, the total key is released to the action of a restoring 120 spring 53, which returns the key 44 and rocks set lever 45, shaft 10 and the arms 45^a and 46 rearwardly. The arms 45^a and 46 on their forward throw as the key 44 is depressed, draw studs 54 on said arms from 125 130

beneath shoulders 55 on thrust bars 56 joined at 57 to resetting levers 58, pivoted on rod 11. The thrust bars rest upon pins 59 on the props 24. When, in a totaling and clearing operation, the props are lowered to connect the counters 20 and their drive members 7, the thrust bars follow until arrested by contact with the studs 54. The restoration of the arms 45^a and 46 by the spring 53, 10 aided, it may be, by a cam (not shown) on the locking means 52, forces the studs 54 against the shoulders 55 of the thrust bars to press them backwardly and rock the resetting levers 58. The arms 60 of said levers 15 58 engage the legs or supports 33, or projections 61 thereon, to disengage the counters from their drive members while the latter remain advanced. Springs 62 return the legs into line with their rests 34 and during 20 the return of the trip rod 26 and props 24, pins 59 displace the thrust bars relatively to the studs 54, to relieve the resetting levers and permit them to drop back to idle position out of the paths of the projections 61 on 25 the legs or supports.

A clear signal mechanism is provided to print a sign adjacent the imprint of the first item introduced into the machine, after a totaling and clearing operation, such clear 30 signal mechanism being set to operate, and thus controlled, by the devices operated in taking a total and clearing the machine. One of the resetting levers 58 has a loose connection 64, Figs. 7, 8 and 9, with a crank 35 65 on a rock shaft 66 journaled in the side frames. An arm 67 fast on said shaft has a pin 68 entered in a slot 69 in a link 70 joined to a connecting member or coupler 71 (Figs. 10, 11 and 12) pivoted to a hammer 72 journaled on rod 73^a adjacent the other hammers 41. A bar 74 on which the keeper 40 is hinged, passes through a slot 75 in the hammer 72 to arrest it on its firing or percussion stroke. The units hammer of the 45 regular printing mechanism carries a lateral projection 76 normally idle, as in Fig. 10, wherein the projection is shown in dotted lines above the coupler 71, the pin 68 lying at the upper end of the slot 69 in link 50 70. When the resetting lever 58 is rocked by its thrust bar 56, just after the printing of the total, it turns the crank 65 and shaft 66 and raises arm 67 and its link 70 to bring the coupler 71 into the path of the setting 55 projection 76. As the hammers of the regular printing mechanism are reset by the bail 43 in the usual manner (not shown), the projection 76 presses against the coupler to set the clear signal hammer 72 and retain 60 it in cocked position against the tension of its spring 63 as long as the units hammer remains cocked. When the thrust bar 56 is tripped to relieve the resetting lever 58, the latter returns to normal position and re- 65 stores the rock shaft 66 and arm 67 to posi-

tion the pin 68 at the lower end of slot 69 (Fig. 11) to enable the coupler to drop back to idle position after the clear signal hammer is fired, and thereby prevent resetting of said hammer until another totaling and 70 clearing operation is performed.

Upon the next effective operation of the machine, whereby an item is printed, after a totaling and clearing operation, the units hammer is tripped and carries the setting 75 and retaining projection 76 away from the coupler 71, thereby releasing the clear signal hammer 72 to the action of its spring 63. The hammer 72 strikes a plunger or firing pin 42^a to drive a type carrier 77 pivoted at 80 78 and carrying a signal type 79, against the platen.

The foregoing construction is old and only constitutes part of the present invention in so far as it is combined with the new 85 parts now to be set forth.

Means has heretofore been provided, as illustrated in patents to Wales 902,125, October 27, 1908, and to McFarland, 880,159, February 25, 1908, to disable the printing 90 and registering mechanisms, respectively, at the will of the operator, and British Patent #23,858 of 1909 shows a mechanism for printing a character adjacent any item which has been printed but not registered, 95 to indicate the fact that the registering mechanism was disabled when such item was printed.

The present invention is directed to improvements on and extensions of these ideas, 100 whereby signs may be printed with or without the imprint of items set up on the keyboard, to indicate any special condition of the mechanisms at any particular operation.

For example, when the printing mechanism was disabled, no provision was made for indicating such fact on the paper, when the machine was operated, and, by manipulation, the machine might seemingly be made to add incorrectly. To enable one at 105 a glance to determine whether the total of a list includes non-printed items, and also to render easy, the detection of improper manipulations, involving the non-print or elimination mechanism, means is associated 110 with the non-print mechanism to effect the imprint of a special sign or character to indicate that the regular printing mechanism was disabled during that operation of the machine. 115

In patent to Wales, 902,125, a device for disabling the regular printing mechanism is disclosed, the same being directly operable by the depression of a key located on the casing of the machine. In the present invention, a similar disabling device 80, (Fig. 6) is normally detained against operation, such detaining means being displaced or controlled by a manually-operable member, as a key 95 on the keyboard. The subse- 120 125 130

- quent operation of the machine then permits the disabling device to shift to effective position. As the operation of the machine is concluded, the disabling device is automatically returned to and detained in idle position. If desired, the key may be maintained depressed to hold the detaining means displaced throughout two or more operations to lock out the regular printing mechanism during successive operations.
- In addition thereto, locking means is provided to hold the key depressed during a single operation, and to prevent the depression of more than one key in the same row or bank, such locking means being held in idle position by a latch which is tripped by the key, and is returned as the machine completes an operation, to release the key and enable the latch to become effective.
- Furthermore, means controlled by the operation of the machine, is provided to prevent the depression of the non-print or any other key in the same bank, after starting and during an operation of the machine.
- Said non-print key controls a special or auxiliary printing mechanism, including positioning mechanism independent of the regular printing mechanism and whereby, during a non-printing operation of the machine, a signal type is brought to the printing line, and an impression device tripped to print said type to indicate the disabled condition of the machine.

Referring more particularly to Figs. 3, 4 and 5, and especially the latter, the means which disables the regular printing mechanism comprises, in the present instance, a comblike, horizontally disposed detaining plate 80, carried by upwardly extending arms pivotally supported at 81 adjacent the trip bars 181.

The trip bars release the individual hammer latches 180, as the type bars 37 are positioned by the levers 36, as heretofore explained, said trip bars being provided with lugs or stops 86 normally located opposite and below the paths of the teeth of the comblike detaining plate 80. A spring 82 tends to maintain the plate 80 in idle position.

Obviously if the plate 80 is swung rearwardly to interpose its teeth 85 above the lugs 86, the trip bars cannot rise to release the individual hammer latches even though the type bars are positioned relatively to the platen in accordance with the values of the depressed keys 2, and no printing would occur.

To effect this result, I provide a shifter or thrust bar 83, for the detaining plate 80, such thrust bar being slotted near its rear end to embrace a rod 84, for guidance, and extending forwardly to an arm 90 on the cross shaft 89 journaled in brackets (Fig. 1) on the side frames 1.

A spring 87 superior to the spring 82 is connected at one end to a rocker 88 fastened to the rock shaft 89, the opposite end of the spring being connected to a link 99 extending upwardly from the tail of a detent 91 ⁷⁰ journaled on the rock shaft 89. The upper end of the link loosely engages one end of a lever 98 pivoted in the keyboard (Figs. 3, 4 and 5) the opposite end of which lever lies beneath a projection or offset 96 on the ⁷⁵ stem 97 of a special or non-print key 95 projecting through the keyboard 3.

Depressing the key or manually-operable member 95 forces the offset 96 against the lever 98, to rock the rear end of the lever ⁸⁰ upwardly and lift the link 99, thereby tensioning the spring 87 to turn shaft 89 and rock the arm 90 rearwardly. This in turn thrusts bar 83 rearwardly, its rear end swinging the comb plate 80 against the tension of ⁸⁵ its spring 82, to interpose the teeth 85 of the comb in the paths of the lugs 86 on the trip bars and thus prevent the latter from releasing the individual hammer latches 180.

The detent 91 (Fig. 3) normally operates ⁹⁰ to hold the thrust bar or shifter 83 against operation, to which end, the detent 91 terminates at its rear, in a hook 91^A adapted to take over a stop 92 on a stop bar 93, whose forward end is connected to an arm or crank ⁹⁵ 94 fast on the rock shaft 89, the rear end of the stop bar being slotted to embrace the guide rod 84.

With the detent in effective position, the rock shaft 89 cannot turn clockwise in which ¹⁰⁰ direction it is urged by the spring 87, owing to the crank 94, stop bar 93 and stop 92. Consequently, the thrust bar 83 is held idle.

Depressing the special key 95 further tensions spring 87, but positively rocks the detent 91 (Fig. 4) so that upon its release of the stop 92, sufficient tension has been stored in drive spring 87 to snap the comb plate 83 rearwardly to effective position.

The shifter is further detained, however, ¹¹⁰ by the contact of arm 18 of the main drive shaft 19, with the rocker 88 of said rock shaft (see Fig. 3), so that depression of the non-print key 95 unlocks the detent 91 only, and the disabling device 80 is held idle until ¹¹⁵ the main drive shaft starts on its forward stroke, whereupon the detaining arm 18 releases the rocker 88 (Fig. 4) to enable the spring 87 to rock its shaft 89 and press the shifter against the detaining plate 80 to ¹²⁰ throw the latter to effective position.

Depression of the spring-restored key 95 also presses its shoulder or offset 96 against the tail 104 of a spring latch 102 pivoted at 103, to trip said latch and thereby release ¹²⁵ a lock plate 100 mounted to slide beneath the key-plate 3 and bearing a keeper 101 to engage the offset 96 and lock the key in operated or depressed position. A spring 105 tends to shift the lock plate to effective posi- ¹³⁰

tion. The keeper 101 is recessed or undercut as at 101^x (Fig. 17) to fit over the offset 96, the lock plate being arrested by contact of the inner end of the recess with the key 5 stem or shoulder.

The tooth 91^a of the detent 91 is of such length as to maintain its engagement with the stop 92, until the key 95 has nearly reached its limit of movement, to insure the 10 operation of the key locking mechanism and thus tend to prevent improper manipulation.

The key 95 is freed from its keeper 101 as the main drive shaft 19 on its return stroke 15 brings a stud 106 on an arm 107 (Fig. 7) fast on the main shaft, against a releasing bar 108, to effect the release of the numeral keys 2, 2, as in the usual Wales type of machine. Said releasing bar carries a tappet 20 109 to strike a finger 110 on a cross shaft 111 to rock said cross shaft and with it a crank 112 (Fig. 18) thereon. Said crank enters a slot in the lock plate 100 and when 25 the cross shaft is rocked, said crank restores the plate to normal position where it is held by the spring latch 102.

The restoration of the plate withdraws the keeper 101 from the non-print key 95, which at once returns under the influence of its 30 spring and restores the lever 98 independently of its link 99, through a pin 113 on the stem 97, (Figs. 4 and 16).

The detaining plate 80 remains effective until the arm 18 on the main drive shaft 35 depresses the rocker 88 (Fig. 3), to withdraw the shifter 83 as well as the stop carrying bar 93, whereupon the link 99 is drawn downwardly through the spring 87 connecting it with rocker 88, and snaps the detent 40 91 behind the stop 92 to hold the disabling mechanism idle during the ordinary registering and listing of items, and spring 82 withdraws the detaining plate.

A stop plate 114 (Figs. 1 and 14) prevents depression of the non-print key 95 from the time the main drive shaft starts on its forward stroke until it completes its return stroke, which is to say, during an 45 operation of the machine. This plate is slid- 50 ingly mounted on studs 115 on the side frame 1 and carries a stop 116. A stud 117 on the usual full stroke segment 118 fast on the main drive shaft 19, bears against a finger 119 on the stop plate when the main shaft 55 is at rest, to normally hold the stop 116 out of the path of the key stem 97 or of the projection 96 thereon. Turning the drive shaft on its forward stroke, withdraws the stud 117 and frees the stop plate to the action of 60 a spring 120, which shifts the stop 116 into the path of the key stem 97 to lock the latter against depression. As the main drive shaft completes its return stroke, the stud 117 contacts the finger 119 to restore the 65 stop plate to idle position (Fig. 1).

The elimination or non-print key 95 also controls the adjustment of a special sign printing mechanism to effect the imprint of a character on the operation of the machine, following the depression of the key, to designate the fact that the regular printing mechanism was disabled during such operation. 70

The recess 101^x of the keeper 101 (Figs. 3, 4 and 5) is of such depth as to permit a predetermined advance of the lock plate 100 75 under the influence of its spring 105, before its arrest by the stem of the depressed elimination or non-print key.

Such forward throw of the locking plate determines the distance through which a positioning bar 121 may advance, the front end of which bar confronts the rear end of the lock plate 100, and is slotted to embrace a guide stud 122. The rear end of said positioning bar is pivoted to an arm 9^a 80 of a lever 36^a journaled on rod 11. A link 36^b connects said lever 36^a with a special type carrier 37^a similar to the regular type carriers 37 and bearing a special type 38^a to indicate a non-print or eliminating operation. 85 This special type carrier preferably lies between the regular units type carrier and the clear signal type carrier 77 (Fig. 2).

The bail 13 contacts the positioning bar 121 to restrain in advance thereof under the 90 influence of a drive spring 123 connected to lever 36^a. The non-print key having been depressed, the lock plate 100 shifts to locking position, and the main drive shaft on its forward stroke withdraws bail 13, which 100 frees the positioning bar to the action of its spring 123. Said spring rocks the lever 9^a, 36^a to advance the positioning bar 121 against the rear end of the lock plate 100 (Fig. 4) to lift the type carrier 37^a and 105 bring the special type 38^a to the printing line in the same manner in which racks 7 are propelled against stops 5. It will be seen that the lock plate serves also as an arrester for the positioning bar, and hence will be 110 referred to as an arrester when its positioning function is under discussion.

An impression device similar to those of the regular printing mechanism, effects the imprint of the special type 38^a, and comprises a hammer 41^a pivoted on rod 73 and driven by a spring 184^a against a plunger or firing pin 42^b (Fig. 12), with which the type 38^a alines when in printing position. The universal resetting bail 43 cocks said 115 hammer 41^a at the same time that it cocks the regular printing hammers 41, and the catch 40 (Fig. 2) holds it in cocked position. An individual latch 180^a similar to the individual latches of the regular printing 120 mechanism holds the hammer 41^a normally idle, said latch being displaced by a trip bar 181^a similar to the regular trip bars and driven by a spring 183^a against the tail of 125 said latch. A lug 182^a on the trip bar con- 130

tacts the under edge of lever 36^a to restrain the trip bar. The lever 36^a when rocked by spring 123, releases the lug 182^a to permit the spring 183^a to thrust the trip bar 181^a 5 against the latch 180^a to displace the latter, after which the catch 40 releases the hammer 41^a which strikes its plunger 42^b and effects the imprint of the special type 38^a. Upon the return stroke of the main drive 10 shaft, the parts are restored to normal positions in the usual manner.

Heretofore, the clear signal mechanism when set, depended for its operation upon the operation of the units hammer 41 of the 15 regular printing mechanism, the throw of which toward its plunger 42 carries the setting and restraining pin 76 with it to free the clear signal hammer 72 to the action of its drive spring 63. Therefore, as far as 20 explained, the disabling of the regular printing mechanism, by the detaining member 80, on the first operation of the machine after a clearing operation, would prevent the imprint of the clear signal because the 25 units hammer would remain idle.

To remedy this condition, I contrive to trip the clear signal printing mechanism independently of the regular printing mechanism, and effect the imprint of the clear 30 signal when the printing mechanism is disabled on the first effective operation of the machine, following a clearing operation. An effective operation of the machine is one wherein an item is set up on the keyboard 35 to be registered, or printed, or both registered and printed. The main drive shaft may be turned to idly operate parts of the machine at any time, providing no numeral keys are depressed, without effecting any 40 change in the relations of the various mechanisms after such idle operation, from the positions occupied thereby prior to such operation.

A stud 124 (Figs. 10, 11 and 12) on the 45 clear signal hammer 72 plays in a slotted arm 125 of a lever 126 loosely mounted on a shaft 127. A tripping link 128 is pivoted to the remaining arm of said lever and extends downwardly toward the base of the machine, 50 the lower end of said link having a slot 129 formed therein, with an offset 130 at its upper end to form a step 131. A tripping member 132 comprising a rocking lever journaled on rod 84, has one arm 133 entered in 55 said slot 129. A guide roll 134 on said arm prevents disconnection of the tripping member and link. A link 135 (Fig. 4) connects the remaining arm of lever 132 with the tripping rod 26, driven from the main shaft 19. The arm 133 of the trip lever oscillates 60 idly in the lower end of the angular slot 129 during the usual operation of the machine. See Fig. 10. The clear signal hammer 72, when cocked, as heretofore explained, rocks 65 the connecting lever 126 through stud 124 to

lower trip link 128 relatively to the arm or tripping toe 133 of the trip lever 132, so that said toe then lies at the upper end of the slot 129 and opposite the offset 130 thereof (Fig. 11).

Depression of the elimination key 95 displaces detent 91 and tensions spring 87 so that when the drive shaft 19 starts on its forward stroke, and withdraws arm 18 from the rocker 88, the rock shaft 89 is turned to 70 shift the thrust bar 83 rearwardly and force the detaining plate 80 to effective position, as hitherto set forth. The rock shaft 89 also swings forwardly an arm 136 (Fig. 4) fast thereon and connected to a switch 137 guided 80 on rod 84 to draw said switch forwardly. The switch, on its forward throw, tensions a flexible connection, as a spring 138 extending between the switch and the link 128 to cause the link to follow the switch, thereby shifting the link relatively to the toe 133 of the trip lever to fit the offset 130 of the slot over the toe and brings the step 131 into the path of the toe. Continued rotation of the main shaft 19 on its forward stroke now 90 rocks the trip lever to press the toe 133 against the step and shift the trip link to rock the connecting lever 126. It will be remembered that the clear signal hammer 72 is held cocked by the engagement of the 95 coupler 71 with the resetting pin 76. The hammer 72 has a releasing throw past its cocked or reset position, however, and as the lever 126 rocks, it swings the hammer 72 forwardly away from the type carrier 37^a, 100 drawing the coupler 71 with it until the latter is freed from the resetting pin 76, whereupon the coupler drops to idle position, aided by a spring 71^a, so that upon the release of the trip link 128 from the trip 105 lever 132, the clear signal hammer is free to make its percussion stroke. (Fig. 12.)

This release is effected by a cam 139 on the link 128, which cam normally lies above the switch 137, but as the link is depressed 110 by the trip lever 132, said cam contacts the switch and crowds the link rearwardly against the tension of the flexible connection 138, to disengage the step 131 and the toe 133. As soon as this disengagement occurs, 115 the spring 63 drives the clear signal hammer 72 against the plunger 42^a to effect an imprint of the clear sign type 79, after which the trip mechanism remains idle until the clear signal is again set, and the elimination 120 key depressed to disable the regular printing mechanism on the first effective operation of the machine after the machine is cleared in the ordinary manner.

A spring 128^a tensioned by the depression 125 of the link lifts the trip link 128 to normal position as soon as the toe and step are disengaged, though such spring may be omitted.

The switch 137 is returned to normal posi- 130

tion at the end of the operation and contacts the link 128 to normally prevent it from swinging forwardly to engage the step 131 with toe 133. Preferably, the special signal 5 38^a is caused to be printed as heretofore explained, on the same initial stroke with the clear signal, so that the two signs (the non-print and the clear signs) lie adjacent each other, to indicate that an item has been registered and not printed, and that the machine was clear when said item was registered. Of course, if the non-print key is 10 not depressed prior to the initial stroke of the drive shaft, the non-print sign will not 15 print, and the clear signal will be printed in the usual manner.

To control the imprint of a special sign opposite or adjacent a particular item or set of items, a special signal key 95^a (Figs. 1 20 and 19), is mounted on the keyboard, preferably in the same bank with the elimination key 95. Depression of said special signal key 95^a presses a shoulder or projection 25 96^a on the stem 97^a thereof, against the tail 104 of latch 102 to release the locking and arresting plate 100. The drive spring 105 shifts said plate to cause a recessed keeper 101^a to fit over the shoulder 96^a and thus 30 lock the key in operated position. The undercut recess 101^y (Fig. 4) of the keeper 101^a varies in depth from the depth of recess 101^x of keeper 101, and preferably is not as deep, so that the arrester 100 is stopped by 35 contact of keeper 101^a with the shoulder 96^a, before it has traveled as far as it does when the elimination or non-print key 95 is depressed. This reduces the advance permitted the positioning bar 121 and the lever 36^a, when released by the withdrawal of the 40 restraining bail 13, on the forward stroke of shaft 19, so that the type carrier 37^a does not rise as high as when key 95 is operated. Consequently the non-print type 38^a in the 45 special type carrier 37^a is not brought opposite the printing line, but a second type 38^b bearing any desired special character mounted in the type carrier 37^a above type 38^a is brought to printing position by the advance permitted the positioning bar 121 by the arrester 100, after which the special signal 50 hammer 41^a is released by the catch 40 to impress said special type on the paper. The main drive shaft on its return stroke, restores the arrester, type carriers, and impression devices, to normal position in the manner heretofore set forth.

The advance of the arrester 100 when tripped by the special signal key 95^a, shifts keeper 101 into the path of the shoulder 96 55 of key 95 to prevent depression thereof.

Furthermore, a stop 140 (Figs. 1 and 14) on the stop plate 114 shifts into the path of the special signal key 95^a to prevent depression thereof at any time during an operation

of the machine, after the main drive shaft 65 has started on its forward stroke.

To enable an item to be printed without being registered, I provide an improved mechanism comprising the usual disabling dogs or members 141 (Figs. 1, 20, and 21) 70 mounted at opposite ends of a rock shaft 142 journaled in the side frames. Heretofore, depression of a key positively connected with said rock shaft swung the dogs under the opposite ends of the axle 21 to support the counters against dropping into engagement with their drive members 7. Such controlling key was located on the case of the machine adjacent said rock shaft, and it was necessary for the operator to stretch across 75 the keyboard to operate the key, the same being true when the former non-print key was to be operated.

One object of this invention is to make the special key mechanisms more accessible, and 80 to group them where they will be handy for operation, as well as to relieve the operator of as much work as possible. To these ends I have arranged said special keys on the keyboard, as shown, and have contrived means 85 set by the special keys to be operated through the actuation of the main drive shaft, to control the devices for disabling registering and the printing mechanisms.

In the present instance, a draft link 143 90 (Figs. 20 and 21) having a hook 144 is pivoted at 145 to one of the disabling dogs 141. A dwell 146 (Fig. 1) on the draft link normally rests on a stud 147, which supports the hook in idle position out of the path of a 95 post or carrier 148, fixed to a moving part of the machine, as the crank 16, for instance. A swinging arm 149 carries the supporting stud. Depression of a second elimination or non-add key 95^b in the same bank with 100 keys 95 and 95^a causes a shoulder 96^b on its stem 97^b to rock an angle lever 150 pivoted to the key board frame, and shift a linkage including a pitman 151 connecting said lever with an arm 152 of a double crank 153 105 journaled in the adjacent side frame 1; and a link 154 which connects the remaining arm 155 of said double crank with a shiftable detainer 156 pivoted at 157 to the side frame 1, to rock said detainer to operative position. 110 The detainer 156 as it rocks to operative position (Fig. 21), tensions a spring 159 connecting an extension 160 of said detainer with a tripping bar 161 joined at one end to the swinging arm 149 and slotted at 162 115 to embrace a pin 163 on the detainer. The tensioning of said spring 159 is due to the longer arc of movement of the extension 160 over that traversed by the forward end of the trip bar 161.

Spring 159 normally presses the trip bar rearwardly to hold one end of the slot 162 against the pin 163 on the detainer and oper-

ates as a yielding link by tensioning which, the trip bar is shifted backwardly, to swing the arm 149 and with it the supporting stud 147, the latter wiping past the dwell 146 to 5 release the draft link and permit the hook 144 to drop over the post 148, so that upon the forward stroke of the main drive shaft 19, and the arm 16 carrying the post 148 the dogs 141 will be drawn under the axle 10 21 to support the latter with its counters 20, out of engagement with their driving members 7 and thus disable the register.

A slow partial depression of the key 95^b without operating the key-locking mechanism 100—101^b, might trip the draft mechanism so that it will engage the post 148 and be drawn forwardly to cause the dogs to operate, and hold the counters idle. The release of the key prior to the completion of 20 the operation of the machine might permit the retraction of the dogs 141 to idle position, and drop the counters into mesh with their drive members 7 during the return of the latter, thereby registering some amount, 25 though rarely that set up on the keyboard.

To prevent such manipulation, the dwell 146 has a continuation 164 shown most clearly in Fig. 22 formed by a flexible cam 165 pivoted at 166 to the draft link and normally held by a spring 167 in position to increase the length of the dwell portion past which the restraining stud 147 must wipe, before releasing the draft link. By thus lengthening the travel of the restraining 30 stud, the distance through which the key 95^b must be depressed before the draft link 143 is released, will be sufficient to enable the shoulder 96^b on stem 97^b of key 95^b to descend far enough to trip the latch 102, and 35 permit a keeper 101^b to fit over the shoulder, to lock the key 95^b and the draft link controlled thereby in set position with the hook 144 engaging the post 148. The remaining keepers 101 and 101^a shift under shoulders 40 45 96 and 96^a of keys 95 and 95^a, to prevent their operation. Obviously, keepers 101^a and 101^b shift under the keys 95^a and 95^b when key 95 is depressed, and so on.

The post or carrier 148 has a back and 50 forth motion, and on the forward stroke of the main drive shaft, said carrier draws the disabling dogs 141 into effective position. To hold the dogs effective during the return of the carrier and the main shaft, a detent 55 60 65 168 is pivoted at 169 to the draft link 143, said detent having a cam nose 170 which, when the draft link is advanced by the carrier 148, rides over a lip 158 on the detainer 156, to lift the detent until it catches on the lip (Fig. 21) and holds the dogs 141 operative during the return stroke of the main drive shaft.

As the main drive shaft 19 on its return stroke approaches its home position, the 65 plate 100 is restored through the cross shaft

111 and crank 112 to release key 95^b which is returned by its key spring 171. The key recedes from the trip lever 150, and thereby enables the tensioned spring 159 to partially restore the detainer 156 to idle position. 70 The spring cannot at this time fully restore the detainer because the latter is still clutched by the detent 168, but when the carrier has nearly completed its return stroke, a flange 172 thereon lifts the detent (Fig. 22), 75 (which has been brought into its path by the partial return of the detainer), to enable the spring 159 to snap the detainer to idle position, and permit restoring springs 173 to withdraw the draft link 143 and dogs 141 80 to their inoperative positions. The tensioned spring 159 also by restoring the detainer, causes stud 163 thereon to pull the trip bar 161 forwardly and the restraining stud 147, and as the stud advances, the draft 85 link 143 moves rearwardly. The contact of the stud 147 with the yielding cam 164 rocks the latter behind the dwell portion 146 to enable the stud to strike an inclined face 174 (Fig. 20) of the draft link which rides up 90 on the restraining stud and guides the dwell portion onto the stud, thereby lifting the draft link 143 to elevate its hook 144 out of the path of the carrier 148. Contact of the forward arm of lever 150 with the shoulder 95^b normally holds the linkage idle.

Depression of the total key operates the releasing link 108 through connecting bar 48 in the usual manner, to restore any numeral keys that may be depressed, and 10 through the releasing link, cross shaft 111, and crank 112, the lock plate or arrester 100 is restored to free the non-add key, or any of the other keys in said bank, if depressed, to enable the mechanisms set by said keys to 10 return to normal positions. In the case of the non-add key, spring 159 (Fig. 5) tensioned by the depression of said key, restores the parts to normal position, when the key is released by the operation of the total key. 11

The keys 95, 95^a and 95^b may also be restored by the error key 175 (Fig. 2) through the releasing link 108, cross shaft 111 and crank 112, said error key operating the releasing link in the manner common to machines of the Wales type, and not shown herein.

In order to prevent the depression of the non-add key either accidentally or otherwise, after the depression of the total key, which 12 would render it impossible to take a total, the stud 54 on arm 46 on the right hand side of the machine, (Figs. 1 and 21), controlled by the total key, is interposed in the path of a lug 179 on the trip bar 161 operated by the 12 non-add key to lock the linkage controlled by the non-add key against effective operation. Upon the release of the total key, said stud is rocked out of the path of the lug. Depression of the total key when the non- 13

add key is depressed, forces the stud 54 against the lug 179 on the trip bar 161 which latter yields idly due to the slot 162 and spring or flexible link 159, to avoid injurious strain on the linkage, which would otherwise be caused by the pressure of stud 54 against lug 179.

The usual repeat key 176 (Fig. 2) may be operated to enable any of the special keys 10 to remain depressed during successive operations, depression of the repeat key displacing the releasing link 108 in the manner common to the Wales type of machine.

The type carrier 37^a has a distinguishing 15 type character 38^c constituting a sign to indicate that the registering mechanism was disabled, during an operation wherein the non-add key was depressed, such sign being printed adjacent the item printed during a 20 non-add operation of the machine. The non-add key 95^b controls the imprint of this sign in the same manner that the non-print and special keys 95, 95^a control the imprints of their respective signs. The recess 101^z of 25 the keeper 101^b is of such depth that when the non-add key is depressed, the arrester 100 is permitted to advance a distance from the positioning bar 121, sufficient to enable the positioning bar, upon the forward 30 stroke of the main drive shaft, to lift said type carrier, until the type 38^c lies opposite the printing line. The trip bar 181^a displaces the individual latch 180^a which normally locks the special sign printing hammer 35 so that when said hammer is released by its catch 40, it strikes the plunger 42^b to effect an imprint of the type 38^c.

Preferably, to familiarize the operator 40 with the special types and cause him to associate the printed impression thereof with the names of the special keys, I place the signs on said keys or key buttons, together with the designations of the keys, as shown in Fig. 2.

45 In the Wales type of machine, the keyboard mechanism is removable from the machine and to preserve this feature, pitman 151 of the non-add mechanism releasably engages arm 152 of the double crank and has a finger piece 177 (Figs. 1 and 20) pressure 50 against which effects its release.

A stop 178 (Figs. 1 and 14) on stop plate 114 prevents depression of the key 95^b during an operation of the machine.

55 Changes may be made in the forms and arrangement of the several parts described and one set of mechanism may be used independently of the others, without departing from the spirit and scope of this invention.

60 What I claim as new is:

1. In a calculating machine, the combination with printing and accumulating mechanisms; of a non-print mechanism adapted to disable the printing mechanism, and includ- 65 ing disabling means normally tending to pre-

vent effective operation of the printing mechanism; a special key; and a key-controlled detent to restrain the disabling means; and auxiliary printing mechanism operable independently of the regular printing mechanism and controlled by the key to print a sign to indicate a non-print operation.

2. In a calculating machine of the kind described, a main drive shaft, printing mechanism normally held in operative relation to said shaft, special sign printing mechanism normally held in inoperative position with respect to said shaft, in combination with means adapted to simultaneously throw the first printing mechanism out, and the special sign printing mechanism into, operative relation with said shaft, so that it will record the non-print condition of the machine in subsequent accumulating operations.

3. In a calculating machine, the combination with registering and regular printing mechanisms; and drive means to operate said mechanisms; of a special member; non-print mechanism released thereby and controlled by the drive means, to render the printing mechanism ineffective; and a recording device controlled by the special member, and operated by the drive means to print a character to indicate that the printing mechanism was disabled, said recording device being independent of the regular printing mechanism and permitted to operate by the non-print mechanism.

4. In a calculating machine, the combination with accumulating devices; of alternately operative printing mechanisms adapted to indicate accumulations; key-controlled means to disable one of said mechanisms and simultaneously therewith, to enable the other; and means to prevent the actuation of said means while the machine is in operation.

5. In a calculating machine, the combination with registering and printing mechanisms; of a normally idle auxiliary printing mechanism; and means to disable the main printing mechanism and set the auxiliary printing mechanism for operation to record a character to indicate that the main printing mechanism was disabled.

6. In a calculating machine, the combination with a printing mechanism; of a non-print device, including a disabling member; means to shift the disabling member to effective position; a detent to normally hold said shift means inactive; and means to displace the detent, and free the shift means for operation.

7. In a calculating machine, the combination with a printing mechanism; of a non-print device, including a member to disable the printing mechanism; means to shift said disabling member to effective position; a detent to normally hold said shift means

inactive; means to trip the detent; means to retire the shift means; and means to restore the disabling member to idle position.

- 5 8. In a calculating machine, the combination with a printing mechanism; of a non-print device, including a member to disable the printing mechanism; a thrust bar to shift said member to operative position; 10 means to operate the thrust bar; a detent to normally hold said thrust bar inoperative; and means to trip the detent.

9. In a calculating machine, the combination with a drive mechanism; and a printing mechanism; of a non-print device, including a disabling member; means controlled by the drive mechanism to shift the disabling member to effective position; a detent to normally hold said shift means 20 inactive; and means to displace the detent, and free the shift means for operation.

10. In a calculating machine, the combination with printing mechanism; of a non-print device, including a member to disable the printing mechanism; means to shift said member to operative position; a detent to hold the shift means inoperative; manually-controlled means to displace the detent; means to release the detent for operation; 30 and means to restore the shift means and disabling member to idle position.

11. In a calculating machine, the combination with a printing mechanism; of a non-print device to disable the printing mechanism, including a disabling member; means to shift said member to operative position; a detent effective to hold the shifting means idle; a manually-controlled means to displace the detent; means to restore the 35 disabling member to idle position; and means to release the detent for effective operation.

12. In a calculating machine, the combination with registering and printing mechanisms; of a non-print mechanism, including a key to release such non-print mechanism for operation; a main drive shaft; and connections between the shaft and non-print mechanism to enable the shaft to effect the operation of the non-print mechanism and to control its withdrawal to idle 50 position.

13. In a calculating machine, the combination with a printing mechanism; of a non-print device, including a disabling member to maintain the printing mechanism idle; a main shaft; means controlled by the main shaft to shift the disabling member to active position, and to control 55 its withdrawal to inactive position; a detent to hold said disabling member inactive; and means to release the detent.

14. In a calculating machine, the combination with a printing mechanism; of a non-print device, including a disabling 60

member to maintain the printing mechanism idle; a main shaft; means controlled by the main shaft to shift the disabling member to active position, and to control its withdrawal to inactive position; a detent to hold said disabling member inactive; means to release the detent; and means to retract the disabling member to inactive position.

15. In a calculating machine, the combination with printing mechanism; and a main drive shaft; of a normally idle disabling member for the printing mechanism; means controlled by the drive shaft, to shift the disabling member to effective position, the drive shaft also effective to restore said shifting means to idle position; a lock normally effective to retain the shifting means idle; means to release the lock; means to retain the lock ineffective; and means controlled by the drive shaft to release the lock-retaining means.

16. In a calculating machine, the combination with a printing mechanism; and a main drive shaft; of a member to disable the printing mechanism; means controlled by the main drive shaft to shift the disabling member to effective position and to permit its return to idle position; means to normally lock the shifting means against operation; a key to control said locking means; and means tripped by the key to hold the detent ineffective, said means controlled by the main drive shaft to release the detent for operation.

17. In a calculating machine, the combination with registering and printing mechanisms; and a main drive shaft; of a non-print mechanism to prevent an effective operation of the regular printing mechanism, including a disabling member; means to shift the disabling member to effective position; a detent to hold said shifting means idle; means to control the detent; and a detaining and restoring member actuated at each operation of the main drive shaft to control the shifting means, when released by the detent.

18. In a calculating machine, the combination with a printing mechanism; of a non-print device to disable the printing mechanism, including a disabling member; means to shift said member to operative position; a detent effective to hold the shifting means idle; a manually-controlled means to displace the detent; means, tripped by the manually-controlled means, to hold said detent displaced; means to restore the disabling member to idle position; and means to release the detent to enable it to return to effective position.

19. In a calculating machine, the combination with a printing mechanism; of a non-print device to disable the printing mechanism, including a disabling member; means to shift said member to operative position;

- 5 a detent effective to hold the shifting means idle; means to displace the detent; a lock to hold the detent displaced; means to restore the disabling member to idle position; and means to release the lock to enable the detent to return to effective position. 70
- 10 20. In a calculating machine, the combination with registering and printing mechanisms; and a drive shaft; of a normally idle member to disable the printing mechanism; means controlled by the drive shaft to shift the member to effective position; and a manually-operated means to free the shifting means for operation. 75
- 15 21. In a calculating machine, the combination with registering and printing mechanisms; and a drive shaft; of a normally idle member to disable the printing mechanism; means controlled by the drive shaft to shift said member to effective position; a manually-operated means to free the shifting means for operation; and means to restore the disabling member to idle position upon the withdrawal of said shifting means by the shaft. 80
- 20 22. In a calculating machine, the combination with registering and printing mechanisms; and a drive shaft; of a normally idle member to disable the printing mechanism; means, controlled by the drive shaft, to shift said member to effective position; a manually-operated means to release the shifting means to the control of the drive shaft; a lock to maintain the manually-operable means in operated position; and means to release the manually-operated means and to return the disabling member to idle position upon the withdrawal of the shifting means. 85
- 25 30 35 40 45 50 55 60 65 23. In a calculating machine, the combination with a drive shaft; and a printing mechanism; of a non-print device, including a member to disable the printing mechanism; means to shift the disabling member to effective position; a detent normally holding said shift means inactive; a detaining and restoring member operated from the main drive shaft, to hold said shift means inoperative while the shaft is at rest, and to return said shift means to idle position; and means to displace the detent. 100
24. In a calculating machine, the combination with a drive shaft; and a printing mechanism; of a non-print device, including a member to disable the printing mechanism; means to shift the disabling member to effective position; a detent to normally hold said shift means inactive; a detaining and restoring member operated from the main drive shaft, to hold said shift means inoperative while the shaft is at rest, and to return said shift means to idle position; means to displace the detent; and means independent of the last-named means to hold said detent displaced. 105
25. In a calculating machine, the combination with a drive shaft; and printing mechanism; of means to disable said printing mechanism, including a disabling member; a spring-driven thrust bar to shift said member into operative position; a detent to prevent effective operation of the thrust bar; means, controlled by the drive shaft, to hold said thrust bar in retracted position; and to restore it to such position after operation; and means to displace the detent and free the thrust bar to the action of its spring, when the drive shaft is moved from its home position. 110
26. In a calculating machine, the combination with a drive shaft; and printing mechanism; of means to disable said printing mechanism, including a disabling member; a spring-driven thrust bar to shift said member into operative position; a detent to prevent effective operation of the thrust bar; means, controlled by the drive shaft, to hold said thrust bar in retracted position, and to restore it to such position after operation; means to displace the detent and free the thrust bar to the action of its spring, when the drive shaft is moved from its home position; and means released by the drive shaft to hold said detent and detent-displacing means in displaced position. 115
27. In a calculating machine, the combination with a drive shaft; and printing mechanism; of means to disable said printing mechanism; including a disabling member; spring-propelled mechanism to shift said disabling member to operative position; a detent to prevent effective operation of the shifting means; means to displace the detent and tension the spring; and means, controlled by the drive shaft, to hold the shifting means idle until the shaft leaves its home position on its forward stroke, and to restore the shifting means to idle position on its return stroke. 120
28. In a calculating machine, the combination with a printing mechanism; of a non-print device, including a disabling member; a shifter for said member; a detent to hold said shifter idle; means to displace said detent; means to lock said detent displaced until the disabling member is operated; means to release said lock to free the detent; and means to restore the shifter to idle position to permit the disabling member to return to idle position. 125
29. In a calculating machine, the combination with a printing mechanism; of a non-print device, including a disabling member; a shifter for said member; a detent to hold said shifter idle; means to displace said detent; means to lock said detent displaced until the disabling member is operated; means to release said lock to free the detent; means to restore the shifter to idle position to permit the disabling member to return to 130

idle position; and means to return the disabling member to idle position.

30. In a calculating machine, the combination with a drive shaft; and a printing mechanism; of a non-print device to prevent effective operation of the printing mechanism, including a disabling member; a shifter for said member; a detent effective to hold the shifter idle during a printing operation of the machine; means to displace said detent; a latch tripped by the last-named means; a keeper, normally held idle by the latch, to maintain the detent displaced; means operated from the drive shaft, to withdraw the keeper to release the detent; and means to restore the disabling member to idle position.

31. In a calculating machine, the combination with printing, and registering mechanisms; and a drive shaft; of a non-print device to prevent effective operation of the printing mechanism, including a disabling member; a shifter to thrust said member into operative position; a rock-shaft with which said shifter is connected; a stop connected with said rock shaft; a detent normally lying in the path of the stop to prevent operation of the shifter; a manually-operated means to displace the detent; a spring tensioned by the manually-operated means to actuate said shifter; a latch tripped by said manually-operated means; a keeper freed by said latch to maintain the detent idle; means controlled by the drive shaft to release the shifter to the action of its drive spring, when the drive shaft is turned on its forward stroke, and to restore said shifter to idle position on the return stroke; and means also controlled from the drive shaft to release the keeper and thereby free the detent for operation.

32. In a calculating machine, the combination with registering, and printing mechanisms; and a drive shaft; of a non-print device, including a normally-idle disabling member; means to shift said member to effective position; a detent to prevent operation of the shifting means on a printing stroke; restraining and restoring means controlled by the drive shaft, to hold the shifting means idle and to restore the same to idle position after an operation; means to displace the detent to free the shifting means for action, when the restraining and restoring means is withdrawn; a lock to hold the detent displaced; and means to release the lock to free the detent for action.

33. In a calculating machine, the combination with accumulating, and printing mechanisms; of non-print mechanism, including a member to disable the printing mechanism; and means operable as an incident to an operation of the machine, to effect the operation of the disabling member.

34. In a calculating machine, the combina-

tion with a printing mechanism; of normally idle disabling means for the printing mechanism, operable as an incident to the operation of the machine; and means to determine the operation of the disabling means. 70

35. In a calculating machine, the combination with a printing mechanism; of a non-print device, including a disabling member for the printer mechanism; means tending to shift the disabling member to effective 75 position; means operable incidentally to the operation of the machine to control the shifting means; a detent to hold the shifting means inactive; and means to displace the detent. 80

36. In a calculating machine, the combination with a main drive shaft; and a printing mechanism; of non-print mechanism, including normally locked means to disable the printing mechanism; means to release 85 the disabling means for operation; and means controlled by a moving part of the machine operable with the main drive shaft, to control the operation of the disabling means. 90

37. In a calculating machine, the combination with accumulating and printing mechanisms; of a normally idle disabling member for the printing mechanism; means controlled by a moving part of the machine and 95 operable incidentally to an operation of the machine; to render the disabling member effective; and a displaceable latch to restrain the last-named means.

38. In a calculating machine, the combination with accumulating and printing mechanisms; of a normally idle disabling member for the printing mechanism; means controlled by a moving part of the machine and operable incidentally to an operation 100 of the machine, to render the disabling member effective; a displaceable latch to restrain the last-named means; and automatically released locking means to hold the latch displaced. 105

39. In a calculating machine, the combination with printing mechanism; and a main drive shaft; of a disabling member for the printing mechanism; shifting means for the disabling member, controlled from the 115 main drive shaft; a detent to normally lock the shifting means against operation; means to displace the detent; a combined keeper and arrester to lock the detent in idle position; a typecarrier having a type positioned 120 by the arrester in printing position; means to effect the imprint of the type while the printing mechanism is disabled; and means controlled from the main drive shaft, to release the detent for operation. 125

40. In a calculating machine, the combination with registering, and printing mechanisms; of a non-print mechanism to prevent an effective operation of the printing mechanism and to record a character to in- 130

dicate that the printing mechanism was disabled, including a disabling member; a detent to hold said member idle; a printing device controlled by the non-print mechanism, comprising impression means; a typecarrier having a type; a positioning bar with which the type carrier is connected; an arrester; a manually-operated device to control the arrester, and the detent; a keeper to hold said manually-operated device in operated position; means to shift the disabling member to operative position; and means to restore the typecarrier, the arrester and the disabling member to their normal positions.

41. In a calculating machine, the combination with registering, and printing mechanisms; and a main drive shaft; of a non-print mechanism to prevent an effective operation of the regular printing mechanism, and including a disabling member; means to shift the disabling member to effective position; a detent to hold said shifting mechanism idle; a manually-operated member to control the detent; a detaining and restoring member actuated at each operation of the main drive shaft, to control the shifting mechanism when released by the detent; a printing device controlled by the manually-operated member and comprising an impression hammer; a typecarrier having a type; a positioning bar with which the typecarrier is connected; a restraining and restoring means actuated at each operation of the main drive shaft, to free the positioning bar and restore it to normal position; a shiftable arrester tripped by the manually-operated member to check the advance of the positioning bar; and means to return the arrester to normal position.

42. In a calculating machine, the combination with registering, and printing mechanisms; of a non-print mechanism to prevent an effective operation of the regular printing mechanism, including a disabling member; and a special printing mechanism to print a character to indicate that the regular printing mechanism was disabled; an arrester to normally restrain the special printing mechanism against actuation; a detent to normally maintain the disabling member idle; and means to trip both the arrester and the detent.

43. In a calculating machine, the combination with registering, and printing mechanisms; of means to disable the printing mechanism; and a special printing mechanism to print a character to indicate that the regular printing mechanism was disabled; an arrester to normally hold the special printing mechanism against actuation; a detent to normally maintain the disabling means idle; restraining and restoring members to coöperate with the special printing mechanism, and with the disabling means,

respectively, to control said devices; and means to trip both the arrester and the detent.

44. In a calculating machine, the combination with registering, and printing mechanisms; of means to disable the printing mechanism; and a special printing mechanism to print a character to indicate that the regular printing mechanism was disabled; an arrester to normally restrain the special printing mechanism against actuation; a detent to normally maintain the disabling means idle; a manually-controlled member to trip both the arrester and the detent; and means to lock the manually-controlled member in operated position until the functions of the disabling means and special printing mechanism have been accomplished.

45. In a calculating machine, the combination with a printing mechanism; of a non-print device to prevent the operation of the printing mechanism, including a disabling member; a shifter for said member; a detent to hold said shifter inactive; manually-controlled means to displace the detent; a shiftable arrester; a latch to hold said arrester normally retracted, and tripped by said manually-controlled means; a keeper on the arrester, to lock the manually-controlled means in operated position, to hold the detent displaced, and to check the advance of the arrester when the latch is released; a positioning bar; a typecarrier connected therewith; a restraining and restoring member to hold said positioning bar in, and return it to, retracted position; drive means to propel the positioning bar against the arrester when the restraining and restoring member is withdrawn, to position the type; means to return the arrester, to free the manually-controlled means and enable the detent to become operative; and means to restore the shifter and disabling member to idle position.

46. In a calculating machine, the combination with accumulating and printing mechanisms; of means to disable the printing mechanism; sign printing mechanism to print a character to indicate that an operation of the accumulating mechanism has taken place while the printing mechanism was disabled; and a single device to control the sign printing mechanism and the disabling means.

47. In a calculating machine, the combination with accumulating and printing mechanisms; of means to disable the printing mechanism, and operable as an incident to the operation of the machine when accumulating; sign printing mechanism to print a character to indicate that an operation of the accumulating mechanism has taken place while the printing mechanism was disabled; and a single device to control the sign printing mechanism and the disabling means.

48. In a calculating machine, the combina-

- tion with accumulating and printing mechanisms; of means to disable the printing mechanism; a detent normally restraining said means against operation; sign printing mechanism to permanently indicate the disassembly of the printing mechanism; and a single device to disengage the disabling means and detent relatively to each other, and to control the sign printing mechanism.

5 49. In a calculating machine, the combination with registering, and printing mechanisms; of independently operable means to disable the registering and printing mechanisms, respectively; a special printing mechanism, to print suitable differentiating symbols to indicate the operation of the machine with one or the other of said disabling means effective; and keys to set the respective independently-operable means for effective operation, and control the special printing mechanism, the respective keys bearing symbols similar to those impressed by the respective types.

10 50. In a calculating machine, the combination with registering, and printing mechanisms; of disabling members for the respective mechanisms, including independent, manually-operable members; a typecarrier bearing signal types; a positioning bar connected therewith; drive means to advance the bar; means controlled by the manually-operable members to arrest the bar at different points in its advance; and impression means to print the character brought to the printing line, to designate the particular disabled condition of the machine at that operation.

15 51. In a calculating machine, the combination with registering, and printing mechanisms; of disabling members for the respective mechanisms, including keys separately depressible to disable either of said mechanisms; a shiftable arrester tripped by the keys; stops on the arrester to contact the depressed key to check the arrester at different points in its travel; a positioning bar; drive means to propel said bar against the arrester; a typecarrier connected with said bar and positioned relatively to the printing line according to the advance permitted the positioning bar by the arrester; and impression means to print the character brought to the printing line, to designate the particular disabled condition of the machine at that operation.

20 52. In a calculating machine, the combination with registering, and printing mechanisms; of disabling members for the respective mechanisms, including keys separately depressible to disable either of said mechanisms; a shiftable arrester tripped by the keys; stops on the arrester to contact the depressed key to check the arrester at different points in its travel; a positioning bar; drive means to propel said bar against the

25 53. In a calculating machine, the combination with registering, and printing mechanisms; of a sign printing device to record signs to designate various conditions of which the machine is susceptible; said sign printing device including manually-operable members; mechanisms to affect the operation of the machine, and set for action by said manually-operable members; a main drive shaft to control the shifting of said mechanisms to effective position; an arrester common to all the manually-operable members and tripped thereby, to shift varying distances determined by the particular manually-operable member depressed; and printing means common to said manually-operable members, and carrying types, said arrester adapted to check the printing means to position the proper type in printing position to record the particular condition of the machine.

30 54. In a calculating machine, the combination with accumulating and printing mechanisms; of independently operable means to disable said mechanisms, respectively; sign printing mechanism to print symbols to indicate the operation of the machine with one or the other of the disabling mechanisms effective; and means to control the independently operable disabling means and the sign printing mechanism.

35 55. In a calculating machine, the combination with accumulating and printing mechanisms; of independently operable means to disable said mechanisms, respectively; sign printing mechanism to print symbols to indicate the operation of the machine with one or the other of the disabling mechanisms effective; and keys to set the respective independently operable disabling means to be operated, as an incident to the effective operation of the machine, and to control the sign printing mechanism.

40 56. In a calculating machine, the combination with registering, and printing mechanisms; of a special printing mechanism, including a typecarrier; type characters mounted therein; a series of keys bearing designations to indicate their purpose; mechanism intermediate the typecarrier and keys and controlled by any one of said keys to adjust the typecarrier relatively to the printing line; the respective keys also bearing characters similar to those impressed by the types, adjusted by the several keys.

45 57. In a calculating machine, the combination with registering, and printing mechanisms; of independently operable means to disable said mechanisms, respectively; sign printing mechanism to print symbols to indicate the operation of the machine with one or the other of the disabling mechanisms effective; and keys to set the respective independently operable disabling means to be operated, as an incident to the effective operation of the machine, and to control the sign printing mechanism.

50 58. In a calculating machine, the combination with accumulating and printing mechanisms; of independently operable means to disable said mechanisms, respectively; sign printing mechanism to print symbols to indicate the operation of the machine with one or the other of the disabling mechanisms effective; and keys to set the respective independently operable disabling means to be operated, as an incident to the effective operation of the machine, and to control the sign printing mechanism.

55 59. In a calculating machine, the combination with accumulating and printing mechanisms; of independently operable means to disable said mechanisms, respectively; sign printing mechanism to print symbols to indicate the operation of the machine with one or the other of the disabling mechanisms effective; and keys to set the respective independently operable disabling means to be operated, as an incident to the effective operation of the machine, and to control the sign printing mechanism.

60 60. In a calculating machine, the combination with accumulating and printing mechanisms; of independently operable means to disable said mechanisms, respectively; sign printing mechanism to print symbols to indicate the operation of the machine with one or the other of the disabling mechanisms effective; and keys to set the respective independently operable disabling means to be operated, as an incident to the effective operation of the machine, and to control the sign printing mechanism.

65 61. In a calculating machine, the combination with accumulating and printing mechanisms; of independently operable means to disable said mechanisms, respectively; sign printing mechanism to print symbols to indicate the operation of the machine with one or the other of the disabling mechanisms effective; and keys to set the respective independently operable disabling means to be operated, as an incident to the effective operation of the machine, and to control the sign printing mechanism.

- nation with registering, and printing mechanisms; of a sign printing device, including a manually-operated member; a shiftable arrester controlled thereby; a positioning 5 bar; a typecarrier connected therewith; drive means to propel said positioning bar until stopped by the arrester, to position the type in the typecarrier relatively to the printing line; and impression means to 10 print the character brought to the printing line.
58. In a calculating machine, a character printing mechanism, including several keys; an adjustable arrester to coöperate with the 15 several keys, to shift through relatively different lengths of travel depending on the particular key depressed; stops on the arrester to contact the depressed key to check the arrester at different points in its travel; 20 a positioning bar; drive means to propel the bar against the arrester; a restraining and restoring member for said bar; a typecarrier connected with the bar and having several types, any of which may be positioned 25 relatively to the printing line, depending upon the extent of travel permitted the positioning bar by the arrester; and impression means to print the character brought to the printing line.
59. In a calculating machine; a character printing mechanism, including several keys; an adjustable arrester having a series of 30 stops to contact the key stems of the respective keys, to permit the arrester to shift 35 different distances, depending upon the key depressed; and to lock the depressed key in operated position and the remaining keys against operation; type positioned relatively to the printing line by the arrester; an impression 40 device to print the character positioned opposite the printing line; a latch to normally hold the arrester at one end of its path and tripped by any of said keys; means to restore the arrester to release the 45 depressed key and free the other keys for operation; and a lock effective with each operation of the machine to prevent depression of any of said keys during such operation.
60. In a calculating machine, the combination with printing mechanism, including an impression device; a typecarrier; a positioning bar; means to propel said bar in one direction; and a restraining and restoring 55 mechanism therefor; of an adjustable arrester; a latch to normally hold the arrester adjacent the positioning bar, to arrest the latter during an operation of the machine; a series of keys, relatively to 60 which the arrester is shiftable, to release the latch; stops on the arrester to contact the depressed keys to check the advance of the arrester, and position the desired type relatively to the printing line; a lock effective 65 at each operation of the machine to prevent

the depression of any of said keys during such operation; and means to restore the arrester to free the depressed key and enable the latch to operate.

61. In a calculating machine, the combination with a registering mechanism; of a printing mechanism, including several manually-operated members; an adjustable arrester controlled by any of said members, and adapted to shift relatively thereto; a 70 positioning bar; a typecarrier connected with the bar, and having several types; drive means to propel the bar against the arrester, to position the desired type relatively to the printing line; a restraining and 75 restoring member for said positioning bar and typecarrier, shiftable into and out of the path of said positioning bar; and an impression device to effect the imprint of that type which is positioned at the printing line. 80

62. In a calculating machine, the combination with a registering mechanism; and a drive shaft; of a printing mechanism, including a shiftable arrester; a manually-operated member to control said arrester; a 90 stop on the arrester to contact the member and check the throw of the arrester; a positioning bar; driving means to propel the bar against the arrester; a typecarrier positioned 95 relatively to the printing line by the positioning bar; a restraining and restoring means shiftable into and out of the path of said bar; and impression devices to effect the imprint of the type.

63. In a calculating machine, the combination with a registering mechanism; and a drive shaft; of a printing mechanism, including a shiftable arrester; a manually-operated member to control said arrester; a 100 stop on the arrester to contact the member and check the advance of the arrester; said stop also effective to lock the manually-operated member in depressed position; a positioning bar; driving means to propel the bar against the arrester; a typecarrier positioned 105 relatively to the printing line by the positioning bar; a restraining and restoring means shiftable into and out of the path of said bar; impression devices to effect the imprint of the type; and means to restore 110 the arrester to normal position.

64. In a calculating machine; a character printing mechanism, including several depressible keys; a normally retracted arrester having a series of stops to contact the operated keys to check the arrester when it has advanced different distances depending upon the key depressed; a positioning bar; a typecarrier bearing types, and controlled by the positioning bar; means to advance the positioning bar against the arrester to position the types relatively to the printing line; a restraining and restoring member for the positioning bar; impression means to print the character brought to the printing line; 125 130

a lock for the arrester released by the depression of any of said keys; and means to restore the arrester to retracted position.

65. In a calculating machine, the combination with printing mechanism, including an impression device; a typecarrier; a positioning bar; means to propel said bar in one direction; a main drive shaft; and a restraining and restoring mechanism therefor;
- 10 of an adjustable arrester; a latch to normally hold the arrester adjacent the positioning bar to arrest the latter during an operation of the main drive shaft; a series of keys, relatively to which the arrester is
- 15 shiftable, to release the latch; stops on the arrester to contact the keys depressed, to interrupt the throw of the arrester, and position the desired type relatively to the printing line; and means to restore the arrester
- 20 to free the depressed key and enable the latch to operate.

66. In a calculating machine, the combination with a drive shaft; a typecarrier bearing types; a positioning bar connected therewith; and a restraining and restoring means for said bar and typecarrier; of a keyboard, including a bank of keys; a shiftable arrester for the positioning bar; a latch tripped by any of said keys to release the arrester;

25 keepers on the arrester to lock the depressed key in operated position and the remaining keys against depression; said keepers also adapted to check the arrester at different points in its travel, to position the types in the typecarrier relatively to the printing line; and means operated by the drive shaft to restore the arrester to free the depressed key and enable the latch to become effective.

67. In a calculating machine, the combination with a drive shaft; a typecarrier bearing types; a positioning bar connected therewith; and a restraining and restoring means for said bar and typecarriers; of a keyboard, including a bank of keys; a shiftable arrester for the positioning bar; a latch tripped by any of said keys to release the arrester; keepers on the arrester to lock the depressed key in operated position and the remaining keys against depression; said
- 50 keepers also adapted to check the arrester at different points in its travel to position the types in the typecarrier relatively to the printing line; means operated by the drive shaft to restore the arrester to free the depressed key and enable the latch to become effective; and a lock plate carrying
- 55 stops and released by the drive shaft on its forward stroke, to prevent depression of any of said keys during an operation of
- 60 the machine.

68. In a printing mechanism, the combination with a series of keys; of a shiftable arrester; means to advance the arrester; a lock to hold the arrester in normal position,

65 and controlled by the keys; stops on the ar-

rester to contact the operated key to check the arrester at various points in its travel; a positioning bar; means to advance the positioning bar against the arrester; and a typecarrier positioned relatively to the printing line by the advance permitted the positioning bar by the arrester.

69. In a printing mechanism, the combination with a series of keys; of a shiftable arrester; means to advance the arrester; a lock to hold the arrester in normal position, and controlled by the keys; stops on the arrester to contact the operated key to check the arrester at various points in its travel; a positioning bar; means to advance the positioning bar against the arrester; and a typecarrier positioned relatively to the printing line by the advance permitted the positioning bar by the arrester; locks on the arrester to hold the keys in the positions occupied at the beginning of the operation of the machine; and means to return the arrester to normal position.

70. In a printing mechanism, the combination with a typecarrier; a positioning bar connected therewith; and means to advance the positioning bar; of a key; an adjustable arrester for the positioning bar; means to advance the arrester; and a lock to hold the arrester in normal position, and tripped by the key to enable the arrester to advance until stopped by the key.

71. In a printing mechanism, a combined key lock and type-positioning means, including a series of keys; a variably shiftable arrester to coact therewith; means to advance the arrester against the keys; means controlled by the keys to lock the arrester in normal position; means controlled by the arrester to lock the keys against operation after the advance of the arrester; a typecarrier; a positioning bar to control the carrier; means to advance the positioning bar until it contacts the arrester, to position a predetermined type at the printing line; and means to return the arrester to normal position.

72. The combination of a printing mechanism, including a series of keys; an adjustable arrester having a series of stops to contact the respective keys, to check the arrester in different positions, depending upon the key depressed; locks on the arrester to hold the depressed key in operated position and the remaining keys against operation; types positioned relatively to the printing line by the arrester; and means to restore the arrester to release the keys.

73. The combination of a printing mechanism, including a series of keys; an adjustable arrester having a series of stops to contact the respective keys, to check the arrester in different positions, depending upon the key depressed; a latch to hold the arrester in normal position and tripped by the keys;

- locks on the arrester to hold the depressed key in operated position and the remaining keys against operation; types positioned relatively to the printing line by the arrester; and means to restore the arrester to release the keys.
74. In a calculating machine, the combination with registering, printing, and clearing mechanisms; of a clear signal mechanism to automatically print a sign as incident to the next effective operation of the machine; after a clearing operation, irrespective of the operation of the printing mechanism.
75. In a calculating machine, the combination with accumulating, printing and clearing mechanisms; of a clear signal mechanism, to automatically print a sign as an incident to the first effective operation of the machine, after a clearing operation; and means to effect the printing of the clear sign without an accompanying operation of the regular printing mechanism.
76. In a calculating machine, the combination with accumulating, and clearing mechanisms; of a clear signal mechanism to automatically print a sign as an incident to the first effective operation of the machine after a clearing operation; regular printing mechanism to restrain the clear signal, when set, from printing during idle strokes of the machine; and means to effect the printing of the clear sign while the regular printing mechanism remains inoperative.
77. In a calculating machine, the combination with accumulating, printing, and clearing mechanisms; of a clear signal mechanism, to print a sign as an incident to the first effective operation of the machine after a clearing operation; means controlled by the printing mechanism to restrain the clear signal, when set, from printing during idle strokes of the machine; and means to effect the disengagement of the clear signal mechanism from the printing mechanism to enable the clear signal to print while the regular printing mechanism remains inoperative.
78. In a calculating machine, the combination with accumulating, and printing mechanisms; a keyboard on which items to be accumulated and printed are set up; a clearing mechanism; and means to disable the printing mechanism; of special printing devices operable independently of the printing mechanism, and as an incident to an operation of the machine in accumulating the first item set up on the keyboard after the machine has been cleared, to print suitable characters to designate the fact that at such operation the machine was clear and that the printing mechanism was disabled.
79. In a calculating machine, the combination with registering, and printing mechanisms; a clearing mechanism; and a clear signal mechanism set by said clearing mecha-
- nism when operated; of a non-print mechanism to disable the regular printing mechanism and control the clear signal mechanism when set.
80. In a calculating machine, the combination with registering, printing, and clearing mechanisms; and a clear signal mechanism set in a clearing operation, and automatically operated with the imprint of the first item introduced into the machine after such clearing operation, to print a character adjacent said first item; and including an impression device controlled by the regular printing mechanism; of a non-print mechanism to disable the regular printing mechanism and print a signal to indicate such disabled condition; and means controlled by the non-print mechanism to effect an operation of the clear signal mechanism provided the latter is set.
81. In a calculating machine, the combination with registering, printing, and clearing mechanisms; and a signal printing means to print a character as an incident to the printing of the first item introduced into the machine after a clearing operation; said signal printing means including a hammer held in cocked position by the printing mechanism; of a non-print device to disable the printing mechanism and print a signal indicating such disabled condition; and means controlled by the non-print device to free the hammer from the regular printing mechanism, when said hammer is in cocked position.
82. In a calculating machine, the combination with accumulating and printing mechanisms; a clearing mechanism; and a clear signal printing mechanism controlled by the clearing mechanism, said clear signal printing mechanism being set for operation and held in set position by the printing mechanism; of a non-print mechanism to disable the printing mechanism; sign printing mechanism controlled by the non-print mechanism to print a sign indicating that the printing mechanism is disabled; said non-print mechanism also adapted to release the clear signal printing mechanism when set, from the disabled printing mechanism.
83. In a calculating machine, the combination with a keyboard; and registering and printing mechanisms; of a clear signal mechanism, including a special character automatically impressed on the paper with the printing of the first item, after the machine has been cleared; a non-print mechanism to prevent effective operation of the regular printing mechanism, including a special character to be printed to indicate that the printing mechanism was disabled when an item was registered; and means to effect the printing of the clear signal character with the non-print character when the regular printing mechanism is disabled.

on the first effective operation of the machine after a totaling and clearing operation.

84. In a calculating machine, the combination with registering, and printing mechanisms; of a clear signal device, including a special character automatically printed with the imprint of the first item after the machine is cleared; means to disable the printing mechanism; and means actuated incidentally to the first effective operation, after the machine has been cleared, to print a character designating such disabled condition, adjacent the imprint of the clear signal.

85. In a calculating machine, the combination with registering, printing, and totaling mechanisms; a clear signal mechanism set in the operation of taking a total and clearing the machine; said clear signal mechanism normally operated as an incident to the imprint of the next item introduced into the machine after the clearing operation; and non-print mechanism to disable the regular printing mechanism; of means controlled by the non-print mechanism to effect the operation of the clear signal mechanism when the latter is set, independently of the regular printing mechanism.

86. In a calculating machine, the combination with registering, and printing mechanisms; of a signal mechanism set to print a character indicating a certain condition of the machine; a second signal mechanism to print a different character to indicate another condition of the machine; and trip mechanism between the two signal mechanisms and controlled by one of said signal mechanisms, to effect the operation of the other of said signal mechanisms, when the latter is in set position.

87. In a calculating machine, the combination with registering, printing, and totaling mechanisms; and a signal mechanism, normally automatically operated with the imprint of the first item introduced into the machine after said totaling and clearing operation, to print a character adjacent said first item; and including an impression device independent of, and set to operate with, the regular printing mechanism when said first item is printed; of a non-print mechanism to disable the regular printing mechanism; and means adjusted by the non-print mechanism when set, to effect an operation of the signal mechanism, providing said signal mechanism is in set position.

88. In a calculating machine, the combination with registering, item printing, and totaling mechanisms; a drive shaft; and a signal mechanism, including an impression device normally set for operation by the operation of taking a total and clearing the machine, to print a character adjacent the imprint of the first item introduced into the machine after a totaling and clearing operation; of a non-print mechanism to prevent

an effective operation of the item-printing mechanism; a trip member operated by the drive shaft; an adjustable connection between said trip member and the impression device; and means controlled by the non-print mechanism to enable the adjustment of said connection relatively to the trip member to effect the operation of the impression device, providing the latter is set.

89. In a calculating machine, the combination with registering, printing, and totaling mechanisms; of a clear signal mechanism, normally automatically operated as an incident to the imprint of the first item introduced into the machine after a totaling and clearing operation, to print a designating character adjacent said first item; said clear signal mechanism including a hammer normally independent of the regular printing mechanism; a normally idle coupler controlled by the total mechanism to connect the hammer with the regular printing mechanism, whereby to cock said impression device; and to enable said hammer to print the clear signal when the regular printing mechanism operates, said hammer capable of an additional throw beyond its normal cocked position, to release the coupler from the regular printing mechanism, and free the hammer to print the clear signal; a non-print device to prevent effective operation of the regular printing mechanism; and means controlled by the non-print device to impart said additional throw to the hammer.

90. In a calculating machine, the combination with registering, printing, and totaling mechanisms; and a signal mechanism normally automatically operated to print a character adjacent the first item introduced into the machine after a totaling and clearing operation; and including a hammer normally independent of the regular printing mechanism; and a coupler controlled by the total mechanism to connect the hammer with the regular printing mechanism, whereby said hammer is reset to be operative with the regular printing mechanism; of means to disconnect said coupler from said regular printing mechanism and free the hammer for operation; a non-print mechanism to disable the printing mechanism; and means adjusted by the non-print mechanism to effect an operation of said disconnecting means, providing the hammer is in set position.

91. In a calculating machine, the combination with registering, printing, and total mechanisms; of a signal mechanism set by the operation of the total mechanism when the machine is cleared, to print a character adjacent the first item introduced into the machine after a totaling and clearing operation; said signal mechanism, including a normally idle hammer; a coupler controlled by the total

mechanism to connect the hammer with the regular printing mechanism to set the hammer; said hammer capable of an additional throw beyond its set position to free itself for independent action; a lever connected with the hammer; a trip member driven with each operation of the machine; an adjustable link having a step shiftable into and out of the path of the trip member, 5 said link connected to the lever to adjust the stop relatively to the trip member when the hammer is set; a non-print mechanism to disable the regular printing mechanism; a switch set by the non-print mechanism and connected with the link to shift the step into the path of the trip member; and a cam on the link to contact said switch and shift the step out of the path of said trip member after the hammer is tripped.

92. In a calculating machine, the combination with registering, printing, and total mechanisms; of a signal mechanism set by the operation of the total mechanism when the machine is cleared, to print a character adjacent the first item introduced into the machine after a totaling and clearing operation; said signal mechanism including a normally idle hammer, set to operate with the regular printing mechanism; a lever connected with the hammer and operated thereby when the said device is set; a trip member driven at each operation of the machine; a link having a step normally out of the path of the trip member; said link shifted by the lever when the hammer is set; a switch to maintain the step out of the path of the trip member when the hammer is set; a non-print device to prevent an effective operation of the regular printing mechanism; 40 said switch controlled by the non-print device to shift the step into the path of the trip member, whereby to free the hammer for independent printing; and a cam on the link to contact the switch and release the step from the trip member subsequently to the operation of the hammer.

93. In a calculating machine, the combination with registering, printing, and total mechanisms; of a signal mechanism set by the operation of the total mechanism when the machine is cleared, to print a character adjacent the first item introduced into the machine after a totaling and clearing operation; said signal mechanism including a normally idle hammer, set to operate with the regular printing mechanism; a lever connected with the hammer and operated thereby when said device is set; a trip member driven at each operation of the machine; 55 a link having a step normally out of the path of the trip member; said link shifted by the lever when the hammer is set; a switch to maintain the step normally out of the path of the trip member when the hammer is set; a non-print device to prevent an ef-

fective operation of the regular printing mechanism; said switch controlled by the non-print device to shift the step into the path of the trip member, whereby to free the hammer for independent printing; and 70 means to effect the release of the step from the trip member subsequently to the operation of the hammer.

94. In a calculating machine, the combination with registering, printing, and total mechanisms; of a signal mechanism set by the operation of the total mechanism when the machine is cleared, to print a character adjacent the first item introduced into the machine after a totaling and clearing operation; 75 said signal mechanism including a normally idle hammer, set to operate with the regular printing mechanism; a trip mechanism set with the hammer; a trip member driven at each operation of the machine; a non-print mechanism to prevent an effective operation of the regular printing mechanism, including a manually-operated member; a switch to prevent effective operation of the trip mechanism by the trip member when the hammer is set; and controlled by the manually-operated member, to enable the trip member to operate the trip mechanism and free the hammer for independent printing.

95. In a calculating machine, the combination with registering, printing, and totaling mechanisms; and a signal mechanism automatically operable as an incident to the imprint of the first item introduced into the machine after a totaling and clearing operation thereof, to print a character adjacent said first item; said signal mechanism including a typecarrier having a type; and a hammer to effect an imprint of said type; 100 of non-print mechanism to disable the regular printing mechanism, and to print a character indicating such disabled condition, including a separate typecarrier having a type and an impression device; and means controlled by the operation of the non-print mechanism to effect an imprint of the first-named signal, associated with the imprint of the second-named character, when the printing mechanism is disabled upon the first 105 effective operation of the machine after a totaling and clearing operation.

96. In a calculating machine, the combination with registering mechanism; of non-add mechanism therefor, including a 120 disabling device to render the registering mechanism inoperative; a carrier shiftable at each operation of the machine; normally idle means to connect the disabling device and carrier to bring said device to effective position; means to detain said device in effective position; and means operable upon the return of the carrier to normal position to trip said detaining means and free the disabling device.

97. In a calculating machine, the combination with registering mechanism; of non-add mechanism therefor, including a disabling device to render the registering mechanism inoperative; a carrier shiftable at each operation of the machine; draft mechanism connected to the disabling device, to engage the carrier; means to support said draft mechanism in idle position; 5 a manually-operated member to trip said supporting means; a detent connected with the draft mechanism; a detainer caught by the detent when the disabling device is brought to effective position, to hold said device operative; means to shift the detent; and means on the carrier, into the path of which said detent is shifted, to release the detent as said carrier is restored to normal position, to permit the disabling device to 10 become ineffective.

98. In a calculating machine, the combination with registering mechanism; of a non-add mechanism to render said registering mechanism ineffective, including a disabling device; a manually-operable member; draft mechanism tripped by the manually-operable member, to engage a moving part of the machine and cause the disabling device to become effective; and means to release the draft mechanism, to permit the disabling device to return to idle position.

99. In a calculating machine, the combination with registering mechanism; of a non-add mechanism to render the registering mechanism ineffective, including a disabling device; a carrier shiftable at each operation of the machine; a manually-operable member; draft mechanism tripped by the manually-operable member to engage 35 the carrier to operate the disabling device; locking mechanism to hold the disabling device in operative position; and means to release the locking mechanism to permit the disabling device to return to idle position.

100. In a calculating machine, the combination with registering mechanism; of a non-add mechanism to render the registering mechanism ineffective, including a disabling device; a carrier shiftable at each operation of the machine; a manually-operable member; draft mechanism comprising a hook connected with the disabling device, to engage the carrier to operate said device, means, tripped by the manually-operable member, to normally hold the hook idle; a detent on the draft mechanism to engage a detainer to hold the disabling device in operative position; and means to disengage the detainer and detent to permit the disabling device to return to idle position.

101. In a calculating machine, the combination with registering mechanism; of a non-add mechanism to render the registering mechanism ineffective, including a disabling device; a carrier shiftable at each

operation of the machine; a manually-operable member; draft mechanism tripped by the manually-operable member to engage the carrier to operate the disabling device; a detent connected with the disabling device; 70 a detainer shifted into the path of the detent by the manually-operable member; means to maintain the manually-operable member in depressed position during an operation of the machine; and means to release the detent 75 and detainer to permit the disabling device to return to idle position.

102. In a calculating machine, the combination with registering mechanism; of a non-add mechanism to render the registering mechanism ineffective, including a disabling device; a carrier shiftable at each operation of the machine; a manually-operable member; draft mechanism tripped by the manually-operable member to engage 80 the carrier to operate the disabling device; a detent connected with the disabling device; a detainer shifted into the path of the detent by the manually-operable member; a lock to hold the manually-operable member in depressed position; means actuated in the operation of the machine to release the lock and free the detainer from restraint by the manually-operable member; and a trip to disengage the detent and detainer 90 to permit the disabling device to return to idle position.

103. In a calculating machine, the combination with registering mechanism; of a non-add mechanism to render the registering mechanism ineffective, including a disabling device; a carrier shiftable at each operation of the machine; draft mechanism connected with the disabling device, to engage the carrier; a support to hold the draft 100 mechanism idle; a manually-operable member to trip the support; a lock released by, and serving to hold, the manually-operable member in operated position; a cam face on the draft mechanism to rest on the support 105 to delay the engagement of the draft mechanism with the carrier until the lock for the manually-operable member becomes effective; means to detain the disabling device in effective position; and means to release the 110 manually-operable member, and to displace said detaining means, to permit the disabling device to return to idle position.

104. In a calculating machine, the combination with registering, and printing mechanisms; and a main drive shaft; of a non-add mechanism to render the registering mechanism inoperative, and including a disabling device; a carrier controlled from the main drive shaft to operate said device; a 120 manually-operable member; draft mechanism controlled thereby and connected with the disabling device to engage the carrier; means to detain said disabling device 125 in operative position while the carrier is be- 130

ing restored; and means to trip the detaining means to permit the disabling device to return to idle position.

105. In a calculating machine, the combination with registering mechanism; of a non-add mechanism to render the registering mechanism ineffective, including a disabling device; a carrier shifttable at each operation of the machine; a manually-operable member; draft mechanism tripped by the manually-operable member to engage the carrier to operate the disabling device; a detent connected with the disabling device; a detainer shifted into the path of the detent by the manually-operable member; a lock to hold the detent where adjusted; means actuated in the operation of the machine to release the lock and free the detainer; and a trip to disengage the detent and detainer to permit the disabling device to return to idle position.

25 106. In a calculating machine, the combination with registering mechanism; of a non-add mechanism to render the registering mechanism ineffective, including a disabling device; draft means connected with the disabling device to shift the latter to effective position; a moving part on the machine; said draft means normally lying out
30 of the path of said moving part; a manually-operable member to trip said draft means to effect its engagement with the moving part; and a releasable lock to maintain the disabling device effective during
35 the restoration of said moving part to home position.

107. In a calculating machine, the combination with registering, and clearing mechanisms; of a non-add mechanism, to render the registering mechanism ineffective, including a disabling device; normally idle draft mechanism to shift the disabling device to effective position; a manually-operable member; trip means controlled by said member, to set said draft mechanism in operative position; and a projection on said clearing mechanism entered in the path of the trip mechanism to prevent the operation of said non-add mechanism when the clearing mechanism is set for operation.

108. In a calculating machine, the combination with registering, and clearing mechanisms; of a non-add mechanism to render the registering mechanism inoperative, including a disabling device; a carrier shiftable at each operation of the machine; draft mechanism connected with the disabling device, to effect an operation of said disabling device; a support to hold said draft mechanism idle; a manually-operable member to trip said support, to enable the draft mechanism to engage the carrier; a projection connected with the support and shifted into the path of the clearing mechanism when the draft mechanism is set for

operation; and means operated by the clearing mechanism to restore the manually-operable member, and cause the support to disengage the draft mechanism from the carrier.

109. In a calculating machine, the combination with registering, and clearing mechanisms; of a non-add mechanism to render the registering mechanism inoperative, including a disabling device; a carrier shiftable at each operation of the machine; a draft mechanism engageable with the carrier and connected with the disabling device to effect an operation thereof; a manually-operable member; a shiftable support to normally hold the draft mechanism out of engagement with the carrier; a linkage connecting the manually-operable member and the support, to enable the manually-operable member to trip the support, and including a yielding trip bar capable of movement relatively to the manually-operable member to avoid strain; a spring to hold said bar normally at one end of its throw; and a lug on said bar, entered into the path of the clearing mechanism when the draft mechanism is engaged with the carrier, to be struck by said clearing mechanism when the latter is set; said clearing mechanism effective when set, to prevent the setting of the non-add mechanism. 75 80 85 90 95

110. In a calculating machine, the combination with registering, and clearing mechanisms; of a non-add mechanism to render the registering mechanism inoperative, including a disabling device; a carrier shiftable at each operation of the machine; a draft mechanism engageable with the carrier and connected with the disabling device to effect an operation thereof; a manually-operable member; a shiftable support to normally hold the draft mechanism out of engagement with the carrier; a linkage connecting the manually-operable member and the support, to enable the manually-operable member to trip the support, and including a yielding trip bar capable of movement relatively to the manually-operable member; a spring to hold said bar normally at one end of its throw; a lug on said bar, 100
105
110
115

entered into the path of the clearing mechanism when the draft mechanism is engaged with the carrier, to be shifted by said clearing mechanism when the latter is set, to effect the restoration of the draft mechanism to idle position; said clearing mechanism effective, when set, to prevent the setting of the non-add mechanism; a lock to hold the manually-operable member depressed; and means actuated by the clearing mechanism to release the lock. 125

111. In a calculating machine, the combination with registering and clearing mechanisms; of a normally idle disabling device for the registering mechanism, op- 130

erable as an incident to the operation of the machine; means to adjust the disabling device for operation; and means controlled by the clearing mechanism to release the adjusting means when set, and to prevent the effective operation of the adjusting mechanism.

112. In a calculating machine, the combination with registering, and printing mechanisms; of a non-add mechanism to render the registering mechanism inoperative, and including a disabling device; a carrier shiftable at each operation of the machine; a normally idle draft mechanism connected with the disabling device, to engage the carrier; a manually-operable member to set the draft mechanism to operative position, relatively to the carrier; means to disengage the draft mechanism at the end 20 of the operation; and a printing mechanism set by said manually-operable member, to record a character to indicate the disabled condition of the machine.

113. In a calculating machine, the combination with registering, and printing mechanisms; and a main drive shaft; of a non-add mechanism to render the registering mechanism inoperative, and including a disabling device; a carrier controlled from the main drive shaft to operate said device; a manually-operable member; draft mechanism controlled thereby and connected with the disabling device to engage the carrier; a shiftable arrester also controlled by the 35 manually-operable member; special printing mechanism positioned by said arrester when the machine is operated, to bring a designating character to the printing line; a hammer to print said character to indicate the disabled condition of the machine; means to detain said disabling device in operative position while the carrier is being restored; and means to trip the detaining means to permit the disabling device to re- 40 turn to idle position.

114. In a calculating machine, the combination with registering, printing, and clear signal mechanisms; and a main drive shaft; of a special signal and elimination mechanism, including a special printing mechanism having a type-carrier in which are mounted several types; a series of keys, depression of any of which, controls the position of the type-carrier to locate the desired 55 type opposite the printing line; certain of said keys also effective to set a register-disabling mechanism; and unlock a printer-dis-

abling mechanism, respectively; the printer-disabling mechanism also effective to trip the clear signal mechanism when the latter 60 is set for operation; and means controlled by the main drive shaft to effect the actuation of the respective disabling mechanisms.

115. In an adding and listing machine, the combination with non-add and non-print 65 mechanisms; and a main drive shaft; of means to set the respective mechanisms for operation; and means operated by the main drive shaft to effect the shifting of said mechanisms, when set, to their operative position, respectively.

116. In a calculating machine, the combination with registering, printing and clearing mechanisms, of means to disable the printing mechanism; clear sign printing 75 mechanism to automatically print a sign with the printing of the first item after a clearing operation; and mechanism controlled by the disabling device to effect the printing of the clear sign when the first 80 item entered in the machine after a clearing operation is non-printed.

117. In a calculating machine, the combination with a registering mechanism; means to clear the registering mechanism; printing 85 mechanism, including hammers; and a clear signal mechanism to automatically print a sign as an incident to the next effective operation of the machine, after the registers have been cleared; of means to render the 90 printing mechanism ineffective, and to effect the imprint of the clear sign, notwithstanding the ineffectiveness of the printing mechanism.

118. In a calculating machine, the combination with registering, printing and clearing mechanism; of a clear signal mechanism normally adapted to automatically print a sign as an incident to the printing of the first item entered in the machine after the 100 clearing operation; and means to effect the operation of the clear sign printing mechanism, irrespective of the operation of the printing mechanism.

119. In a calculating machine, the combination of a plurality of sign printing mechanisms; and means controlled by one of said sign printing mechanisms to effect the printing operation of another sign printing mechanism.

JOSEPH F. REIRDON.
In the presence of—
CHAS. V. WILGUS,
FRED ALLEN.
